UNITED STATES PATENT OFFICE.

EARL R. BELL, OF COVINGTON, KENTUCKY, ASSIGNOR OF ONE-FOURTH TO ARTHUR L. EVANS AND ONE-FOURTH TO RUSSELL A. LENOX, BOTH OF COVINGTON, KENTUCKY.

CONCRETE SPREADER MOLD.

Application filed June 23, 1927. Serial No. 200,896.

This invention relates to a concrete spreader mold.

It is aimed to provide an efficient construction whereby the frame for making various lengths of concrete spreaders, is adjustable in a novel manner.

Another object is to provide such a construction wherein wedge-shaped pins may be used if desired to form openings to accommodate bolts to be used in connection with the spreaders.

Another object is to provide the device of such construction as to have relatively movable parts coacting to produce the novel results.

Various additional objects and advantages will in part be pointed out and in part become apparent from a consideration of the description following taken in connection with accompanying drawings illustrating an operative embodiment.

In said drawings:

Figure 1 is a plan view of the mold;

Figures 2 and 3 are opposite end views thereof;

Figure 4 is a longitudinal sectional view on a plane indicated by the line 4-4 of Figure 1;

Figure 5 is a transverse sectional view on a plane indicated by the line 5-5 of Figure 1;

Figure 6 is a perspective view of the base;

Figure 7 is a perspective view of the frame;

Figure 8 is a perspective view of the wedge-pin; and

Figure 9 is a perspective view of one of the concrete spreaders and provided with attaching members.

In carrying out the invention, a suitable base is provided as at 10 which may be adapted for stationary disposition and support in any desired manner. At one end of the base 10 are upstanding plates 11 and 12 spaced by a slot as at 13.

Coacting with the base 10 is a frame or body 14 which may have side walls 15, an end wall 16, a connecting bar 17, and a partition wall 18 secured to the connecting bar and to the front or end wall 16. The frame is slideable over the base 10 with the bar 17 disposed in the rear of the plates 11 and 12 and with the partition 18 and end wall 16 resting directly on said base. The walls 15,

however, depend below the end wall 16, partition 18 and bar 17 so as to overlap the sides of the base and thus constitute a guide for the movement of the frame.

The said coacting base and frame form 60 pockets or mold cavities at 19 and 20, in which spreaders of concrete or the like 21 are adapted to be molded or made, it being obvious that the body 14 through adjustment may vary the size of the spreaders to 65 be made since it varies the distance between the plates 11 and 12 and the end wall 16. The spreaders of concrete made by the device may be used in place of the usual wooden spreaders for concrete mold forms 70 as in the making of concrete walls by pouring.

The plate 11 and end wall 16 in line therewith may have openings 22 and 23, respectively therethrough, to accommodate wedge 75 pins 24, removably, and selectively forming a cylinder, so as to provide an opening in the spreader 21 cast in space 19, such opening being adapted to accommodate bolts that may be inserted to hold the concrete 80 forms together in practice.

On the other hand, the spreader 21 may be of solid concrete and have fastening elements such as metallic nail-accommodating strips 25 fastened at one end therein. The solid spreaders are made in the space 20 since the plate 17 and portion of the end wall 16 opposite the same are imperforate.

Various changes may be resorted to provided they fall within the spirit and scope 90 of the invention.

What is claimed is:

1. A device of the class described comprising a base member, a frame member, one of said members being movable relatively to the other, and one of said members having a plate for coaction with the other member to determine the size of the article to be molded.

2. A mold of the class described having 100 a base provided with an upstanding plate, a body having walls on opposite sides of the plate, a bar carried by the body outwardly of the plate for the purpose specified, and one of said members being movable relatively to the other.

3. A mold of the class described having a base, a plate rising therefrom, a body movable relatively to the base having an end wall, side walls disposed on opposite sides of 110

the plate, and a bar connecting said side walls and disposed on the opposite side of the plate to said end wall.

4. A mold of the class described comprising a base having upstanding plates with a space therebetween, a body slideable on the base having a partition occupying said space, said body having sides engaging the sides of the base, and a cross bar on the body engaging said plates.

5. A mold of the class described having a base, plates rising therefrom having a space therebetween, a body slideable on the base and consisting of an end member, side members extending below the end members and overlapping the sides of the base, a partition extending from the end member and through said space, and a bar connecting said side members and partition and lo-

cated on the opposite side of the plate to the end member.

6. A mold of the class described having a base, plates rising therefrom having a space therebetween, a body slideable on the base and consisting of an end member, side members extending below the end members and overlapping the sides of the base, a partition extending from the end member and through said space, a bar connecting said side members and partition and located on the opposite side of the plate to the end member, one of said plates having an opening and the end member having an opening in line therewith, in combination with a pin for removable accommodation in said opening, for the purpose specified.

In testimony whereof I affix my signature.
EARL R. BELL.
